FOLDING BOX

Samuel Platt, San Francisco, Calif.

Application August 16, 1943, Serial No. 498,812

2 Claims. (Cl. 229—34)

This invention relates to folding boxes and has for one of its objects the provision of a folding box having side walls and a bottom, and which box is adapted to be quickly folded from a single flat sheet of cardboard, or the like, without requiring the use of glue or cement and without requiring the use of slits or enclosed slots for tabs to be held therein.

Another object is the provision of a folding box adapted to be quickly formed from a single sheet of cardboard to provide side walls of double thicknesses, and a bottom wall, and in which box the corners of the box at the ends of the adjacent sides and along the junctures between the sides and bottom are reinforced with double thicknesses of said cardboard, and which box is held in set-up condition without the use of glue, or the like, and without interlocking elements such as enclosed slits or slots receiving tabs therein.

Other objects and advantages will appear in the drawings and description.

In brief explanation of the above objects, the use of the term "folding box" refers to boxes that do not require glue for holding the sides upright or at right angles to the bottom of the box. There are many boxes that are folded from a cardboard sheet but which boxes must employ glue at some point or points in their fabrication to hold them in shape. These boxes or others using staples or any material extraneous to the material of the sheet forming the box are not "folding boxes" within my meaning of the term, or as the term is commonly used in the art of box making. A folding box ordinarily is shipped to the customer in a flat, knocked-down form and the customer folds it, or sets it up, although this is not necessarily so.

Most folding boxes require slits or enclosed slots, and tabs that are cut or formed to releasably lock in such slits or slots. The forming of such slits or enclosed slots is objectionable in that the material from the blanks tends to stick in them and cannot be stripped therefrom without considerable difficulty. Also the setting up of such boxes is difficult for relatively inexperienced persons and even experienced persons many times have trouble and flaps or slits are mutilated. In all instances, the operation is relatively slow. Inasmuch as boxes, after being set up, are seldom, if ever, unfolded, the most desirable structure is one that avoids the above mentioned difficulties, and that provides a neat box free from external visible tabs, slots, etc., and which box is strong and that will not accidentally collapse or

unfold; even when subjected to extraordinary abuse. Such box is provided by my structure.

In the drawings:

Fig. 1 is a plan view of a blank from which the box of my invention is formed. All dash lines in said figure indicated crease or score lines for folding.

Fig. 2 is an enlarged plan view of the blank of Fig. 1 when folded; and looking into the box from its open upper side.

Fig. 3 is a perspective view of one end of the box partially folded to show one stage of the folding process.

Fig. 4 is a perspective fragmentary view of one end of the box when folded. Part of the cover is indicated.

Fig. 5 is a sectional view of part of the box as seen from line 5—5 of Fig. 4.

Fig. 6 is a sectional view of the box as seen from line 6—6 of Fig. 4.

Inasmuch as the cover for my box is identical in structure to the body of the box, only the latter will be described in detail. The cover is adapted to telescopically fit over the body, as indicated in Fig. 4, and therefore, its dimensions may be slightly greater than the dimensions of the body, but structurally nothing is found in the cover that is not in the body.

Referring to the cardboard blank of Fig. 1, the bottom of the box to be formed by folding said blank is indicated at 1. This bottom is rectangular and is bounded along two opposite edges by parallel fold lines 2, while fold lines 3 bound the other two edges. These lines represent folding scores formed in the blank.

Outwardly of scores 2 are generally rectangular extensions that are scored at 4 along lines equally spaced from their outer edges, and parallel with scores 2, thereby defining marginal strips 5 along said edges.

Midway between scores 2, 4 in each extension that is outward of scores 3, the said extensions are scores at 6 parallel with scores 2 respectively adjacent thereto.

Outwardly of scores 3 are generally rectangular extensions that are scored at 7 along lines equally spaced from their outer edges and parallel with scores 3, thereby defining marginal strips 8 along said edges. These strips 8 are each of the same width as each of the strips 5, and scores 7 are spaced from scores 3 substantially the same distance that scores 4 are spaced from scores 2 and parallel with scores 7.

In folding the blank so as to form the box, the extensions outward of scores 2 and at opposite

sides of scores 6 will be folded on themselves and then folded along scores 2 to be at right angles to the bottom 1. In this position the strips 5 will fold along scores 4 to overlie the marginal portions of bottom 1 along scores 2. Thus two of the opposed sides of the box will be formed.

The other two opposed sides will be formed by folding the extensions outwardly of scores 3 at opposite sides of scores 9 on themselves. When these extensions are then folded along scores 3 to positions at right angles to the bottom, the flaps 8 will overlie the marginal portions of bottom 1 along scores 3 the same as marginal portions 5 overlie the marginal portions along scores 2. However, the ends of marginal portions 8 will overlie the ends of marginal portions 5 as will be later described.

In order to hold the double sides, above described, at right angles to the bottom 1, I provide corner pieces on the blank at the adjacent ends of the adjacent extensions.

To best define these corner pieces, the portions of the extensions forming the inner and outer layers of each side of the box will be identified.

The portions 10 of the extensions outwardly of scores 2 and directly adjacent said scores will form the outer layers of two opposed sides of the box, while the portions 11 between scores 4, 5 will form the inner layers respectively adjacent and opposed to layers 10.

The portions 12 of the extensions outwardly of scores 3 form the outer layers of the other two opposed sides of the box, while the portions 13 between scores 7, 9 form the inner layers of said opposed sides.

The corner pieces are each in two parts, but integrally united. Part 14 of each corner piece is preferably rectangular and is bounded by aligned extensions of scores 2, 3 and of scores 6 on three edges, while the fourth edge is free and is in continuation of score lines 9. A diagonal score 15 extends across each part 14 from the intersections of score lines 2, 3 at the corners of the bottom 1.

The second part 16 of each corner piece is integral with and outwardly of each end of each portion 11. The part 16 is also integral with each part 14 being joined therewith along the extensions of scores 6. The juncture between each part 16 and each portion 11 is defined by the extensions of each score 3.

The free edge of each part 14 that is in continuation of scores 9 continues past part 14 to define one free edge of each part 16.

The ends of the marginal strips 5 terminate even with extensions of the score lines 3, and the ends of the inner layers 11 are notched out directly adjoining the ends of strips 5 as indicated at 20.

The depth of each notch 20 is important, it being slightly greater than the width of each strip 8, and the width of each notch in direction at right angles to its depth, or in direction at right angles to strips 5, is slightly greater than the width of each of the tabs 21 that are at the ends of strips 8 and in extension thereof. This "width" of each tab 21 refers to the dimension thereof longitudinally of each strip 7.

Each notch 20 opens outwardly by reason of the fact that each part 16 is cut away along line 22 that extends from the side of notch 20 remote from each strip 5 that is adjacent thereto, to the free edge of each part 16 that is in alignment with the adjacent score 4. Thus any cardboard stock

that might tend to stick in the notch is readily stripped therefrom through the open side of notch 20.

To fold the box, the extensions comprising inner and outer layers 10, 11 are folded on themselves and then are brought to a position at right angles to bottom 1 as seen in Fig. 3. The inherent resiliency of the cardboard along the line of bend that defines the free edge of each side so formed will tend to cause inner layers 11 to swing inwardly into the box at their lower edges. Also, the tendency of the strips 5 to straighten out to coplanar relation to the inner layers will cause them to lie flat against the bottom 1.

The above step will result in the parts 14, 16 being also brought into opposed relation and perpendicular to bottom 1, but the extensions comprising inner and outer layers 12, 13 will still be substantially coplanar with bottom 1. By swinging the pairs of parts 14, 16 toward each other to the positions thereof indicated in Fig. 3, the parts 14 will automatically fold on itself along fold lines 15 to carry the respective layers 12 to positions at right angles to bottom 1. The inner layers 13 (Fig. 3) are then swung over the parts 14, 16 to opposed relation, and as said inner layers swing between the opposed inner layers 11, the tabs 21 will be yieldably bent backward to generally a position at right angles to the respective strips 5 that carry them. As soon as the inner layers 13 are substantially parallel with the layers 12 (the parts 14, 16 being between layer 12 and layer 13 at two opposed sides of the box), the ends of strips 8 and the tabs 21 will slip into the notches 20. Upon release of the folding pressure on layers 13, they will each tend to spring away from the layer 12 adjacent thereto, and a corner 24 (Fig. 6) of each tab 21 will slip between layers 10, 11 (Fig. 5), it being remembered that layers 11 also tend to swing inwardly toward each other at their lower edges at all times. Thus once the box is set up by folding as above described, it is releasably locked against unfolding, and should the user desire to unfold the box, the inner layers 11 must each be tightly pressed against the layer 10 that is adjacent thereto, and also layers 13 must each be pressed tightly against outer layer 12 that is adjacent thereto, and then the operator must bend tabs 21 to swing them out of notches 20. These operations should be simultaneous, a fact which makes the lock that is created a very reliable one.

The tabs 21 are not essential to holding the box in setup form, because the ends of strips 8 will still be held in overlying relation to the ends of strips 5 and in notches 20, even if tabs 21 are removed, but the lock is made more positive by providing the tabs. Thus this invention is not restricted to the use of the tabs.

The structure as described, provides for automatic locking of the walls of the box in proper position when they are folded. No glue, cement, paste, staples, or other material is required. In fact they are not desirable, since there are occasions on which the unfolding of the box is found desirable, and also the use of such glue or other material is expensive, requiring a special machine if the step is to be commercially practical. Obviously, box users purchasing flat blanks for folding to box form are not equipped with such machines.

The box cover 30 (Fig. 4) is identical in structure to the body of the box, and the dimensions are such that it will telescopically fit over the body,

From the structure described, it is further seen that the provision of flaps 5, 8 reinforces the box along the junctures between bottom 1 and outer layers 10. Also the integral juncture between parts 16 and inner layers 11, and between parts 14 and outer layers 19 reinforces the box at the four corners.

Having described the invention, I claim:

1. A rectangular box having a bottom wall, two opposed end walls, and two opposed side walls, all formed from a single sheet of cardboard, said end walls and said side walls being extensions of said bottom wall respectively folded on themselves to provide a double layer of said sheet in which each layer terminates in a marginal strip overlying the bottom wall along each edge of the latter, the marginal strips on said end walls being in overlying relation to the marginal strips on said side walls, laterally and oppositely outwardly opening notches formed in opposite ends of the inner layers of said side walls, the upper edges of said notches extending slantingly downwardly and generally toward each other from the end edges of each inner layer of said side walls, extensions respectively projecting outwardly of the ends of the marginal strips that are on said end walls and through said notches to upstanding positions, each such extension being formed with a corner portion extending between the inner and outer layers of said side walls adjacent the lower end of the slanted upper edge of each of said notches.

2. A rectangular box having a bottom wall, two opposed end walls and two opposed side walls all formed from a single sheet of cardboard, said end walls and said side walls being extensions of said bottom wall respectively folded on themselves to provide a double layer of said sheet in which each inner layer terminates in a marginal strip overlying said bottom wall along each edge of the latter, diagonally foldable corner pieces integral with the outer layers of said side walls and end walls at their adjacent ends, and extensions integral with inner layers of said end walls at their opposite ends and with said corner pieces along one edge of each corner piece, said corner pieces being positioned between said extensions and the outer layers of said end walls, laterally oppositely outwardly opening notches formed in the ends of the inner layers of each side wall adjacent the marginal strips respectively thereon, the upper edge of each such notch extending slantingly downwardly from the end wall adjacent thereto, tabs formed on the opposite ends of the marginal strips that are on the inner layers of said end walls and extending through said notches and upwardly against the outer layers of said side walls with part of the upper portion of each tab disposed between the inner and outer layer of each side wall that is adjacent the lower end of the slanted edge of each notch.

SAMUEL PLATT.
